SUCTION CLEANER

John W. Wolfe, Canton, Ohio, assignor to The
Hoover Company, North Canton, Ohio, a cor-
poration of Ohio

Application August 15, 1931, Serial No. 557,349

8 Claims. (Cl. 15—183)

The present invention relates to suction cleaners in general and particularly to a new and improved suction cleaner rotary agitator. More specifically the invention comprises the provision 5 of a suction cleaner agitator in which adjustable brushes are provided to compensate for bristle wear.

In the modern suction cleaner agitator comprising both rigid beating elements and flexible bristle brushes, the bristle life is a variable dependent upon the type of covering upon which the agitator is used, and upon the quality of the bristle used in the brush itself. The rigid beating element and the brush element in the agitator extend to substantially the same distance 10 from the axis of rotation and, as the rigid beater element, being made of hard smooth metal, is substantially wear-proof, it is apparent that, as the brush bristles become worn and their length decreased, in time they will cease to be a factor 15 in the cleaning of the surface covering and that covering will be contacted only by the rigid beating elements; the brush elements revolving in a circle of lesser diameter and failing entirely to 20 contact the surface covering undergoing cleaning. These brush elements are of relatively small cost and, heretofore, it has been the practice to replace them when worn to such an extent that they no longer perform their intended function. 25 In certain types of agitators complicated mechanisms have been provided to adjust the effective brush lengths but, because of the relatively cheap cost of the brushes, it has not been commercially feasible to provide this mechanism.

In the agitator constructed in accordance with the present invention the brush elements themselves, and the brush seat in the agitator body proper with which they cooperate, are so formed that their effective lengths, that is the height 35 40 which the bristles extend above the surface of the rotor, can be changed by a simple adjustment of the brush relative to the supporting body.

It is an object of the present invention, therefore, to provide a new and improved suction 45 cleaner agitator. A further object is to provide a new and improved rotary agitator for suction cleaners. A still further object is to provide a rotary suction cleaner agitator comprising an adjustable brush. Another object is to provide 50 a rotary suction cleaner agitator comprising a brush which is adapted to be positioned in a plurality of positions relative to the agitator to effect adjustment in the bristle height above the body of the agitator. These and other more 55 specific objects will appear upon reading the fol-

lowing specification and claims and upon considering in connection therewith the attached drawing to which they relate.

Referring now to the drawing in which a preferred embodiment of the present invention is disclosed:

Fig. 1 is a partial side view of a suction cleaner embodying the present invention with the casing of the cleaner broken away and showing the agitator in section therein;

Fig. 2 is a partial side view of an agitator constructed in accordance with the present invention with portions broken away and shown in section;

Fig. 3 is a section upon the line 3—3 of Figure 70 2;

Fig. 4 is a partial section similar to Figure 2 showing the brush in its second, or worn position;

Fig. 5 is a section upon the line 5—5 of Fig- 75 ure 2;

Fig. 6 is a section upon the line 6—6 of Fig- 75 ure 4;

Fig. 7 is a view of a brush element per se;

Fig. 8 is a partial section upon the line 8—8 80 of Figure 4.

In the drawing the present invention is shown embodied in a suction cleaner which is partially shown in Figure 1 which comprises a nozzle 1, and a fan chamber 2, to which the nozzle is interiorly connected, there being a rotatable fan 3 in the fan chamber 2 which is mounted upon the extended end 4 of the motor shaft. The agitator, which is indicated generally by the reference character 6 and which is driven from shaft 4 by means of belt 5, comprises a hollow body 7, which is preferably substantially cylindrical throughout its major portions, and which is provided with longitudinally extending reentrant portions or channels 8 at each side of the pulley 9 which is itself positioned substantially at the longitudinal center of the agitator. The agitator is rotatably mounted upon a stationary supporting shaft 10 which extends longitudinally through the body 7 and carries suitable stationary thread guard members 11 at its ends which serve to protect the body 7 from thread, hair etc. collecting around its end and around the bearing which is positioned between the shaft 10 and the body.

Positioned upon the periphery of the body 7 and formed either separately or integrally therewith, are longitudinally extending beater bars indicated by the reference characters 12, 12. These beaters preferably extend in curves substantially the entire length of the body 7 excepting the

width of the pulley 9. In their preferred embodiment these beating elements 12, 12 extend but a relatively small height above the normal surface of body 7 and lie upon that surface in curves 5 which may be helices and which have common end points.

Within each brush seat 8 is positioned an elongated brush comprising a rigid back 13 in which are seated tufts of bristles indicated generally 10 by the reference character 14. The back 13 is greater in length than the channel 8 within which it is seated and the reduced, stepped ends 15, 15 of the back extend through openings, or recesses 16, 16 at each end of the channel. The 15 shoulders on back 13 which define the beginning of each stepped end is held adjacent an end wall of the channel by means of resilient springs 17, 17 which are carried in the bottom of the brush seats and which urge the brush radially outward 20 from the channel. With a brush in place within its seat and the stepped ends 15, 15 extended under the end walls of the channel 8 the brush is securely locked against accidental displacement, the centrifugal force resulting from the 25 rotation of the agitator serving only to more securely seat it.

The stepped ends 15, 15 of the brush element, it is to be noted, are not of the same width as the remainder of the brush back 13 but are of 30 substantially half the width thereof and, further, these ends are both positioned upon the same side of the back. Reference to the cross sectional views of Figures 5, 6 and 8 discloses that at each 35 end of the channel portion 8 the end wall, in which the recess 16 is provided, extends inwardly to different radial position upon the opposite sides of the channel. From Figures 5 and 8 it is seen that the side of each end wall of channel 8 which extends the greatest distance toward the longitudinal axis is positioned upon the same side of the longitudinal center line of the brush seat as the corresponding side of the opposite end of the channel. It is apparent, therefore, that with the 40 brush positioned as shown in Figure 2 with the projecting ends 15, 15 on the far side of the brush so positioned that they extend below the longest sides of the end walls of the channel that the brush will be located relatively deep in its seat resulting in the desired bristle height above the 45 rotor body 7, the bristles being long when the brush is new. It is in this position that the brush should be seated when new and, to insure that the user will so seat it, the words "New brush-pulley end" is positioned adjacent that end of 50 the brush which is adjacent the pulley when so seated. As the width of the brush back 13 is substantially the width of the brush seat 8 it is apparent that with the brush so seated that it 55 will remain secure until intentionally removed by the operator.

After being used for a considerable time and the brush bristles having become worn so that they no longer extend to the original height above the rotor body it becomes desirable to make an 60 adjustment so that the original height is again attained. To accomplish this object, in the agitator constructed in accordance with the present invention, it is only necessary to remove the brush from its seat, this being easily accomplished by 65 the use of a small tool such as a screw driver which is adapted to seat within a transversely-extending groove 18 across the upper face of the brush back to enable the operator to depress one end of the brush, against the force of the adjacent spring 17, and to shove that end further into the 70

recess 16, thereby permitting the opposite end of the brush to be withdrawn from its recess 16 and thereafter the entire withdrawal of the brush. After the brush has been withdrawn it is reversed end for end so that it assumes the position shown in Figure 4 in which the projecting, reduced ends 15, 15 are positioned upon the near side of the brush and extend under those sides or portions of the end walls of channel 8 which extend radially the shortest distance. The 80 springs 17, 17 perform their function to hold the ends 15, 15 against the walls and the brush is positioned at its maximum radial position, the bristles extending again to their original height above the rotor surface. To insure that the operator will replace the brush in the correct position the words "Worn brush-pulley end" are positioned adjacent that end of the brush which is to be seated adjacent the pulley after the brush has been in use and is to be replaced. 85

From the foregoing it is apparent that applicant has provided a new and improved suction cleaner agitator in which, through the provision of a new and novel structural relationship it is possible for the brush to be adjusted to compensate for bristle wear and thereby increase the 90 effective brush life. 95

I claim:

1. In a suction cleaner agitator, a cylindrical body having therein an elongated brush seat with 105 fixed ends, a removable brush adapted to be selectively seated in one of a plurality of positions in said seat, a plurality of fixed means on said body overlying said brush to oppose centrifugal force and to limit the height thereof above said body, and means on said brush adapted to cooperate with certain of said limiting means in a predetermined manner in each of the various brush positions to determine the brush height above said body. 110

2. In a suction cleaner agitator, a cylindrical body having therein an elongated brush seat with fixed ends, a brush adapted to be reversibly positioned in said seat, stationary means on said seat overlying said brush to determine the height thereof relative to said body in one brush position, second stationary means overlying said brush to position said brush at a greater height in a second brush position, and means on said brush adapted to cooperate with one of said stationary positioning means in a predetermined manner depending on the position of said brush. 115 120

3. In a suction cleaner agitator, a body having an elongated brush seat comprising an end wall formed with an opening, said wall extended lower 130 on one side of a vertically longitudinally-extending bisecting plane than upon the other, a brush adapted to be positioned in said seat and having end portions each adapted to extend into said opening and contact an end wall on one side of 135 said plane, characterized by the fact that the opposite end portions of said brush contact one end wall on opposite sides of said plane upon the reversal of the brush.

4. In a suction cleaner agitator, a body comprising an elongated brush seat having end walls with openings, said openings being of greater height on one side than on the other, a reversible brush positioned in said seat having a portion 140 extended into one side of one of said openings and contacting one side only of the top thereof, a like portion on the opposite end of said brush, characterized by the fact that upon the reversal of said brush the like portion contacts the op- 145 150

posite side of the said opening to effect a different brush height.

5. In a suction cleaner agitator, a cylindrical body with an elongated brush seat therein having fixed ends and spaced pairs of cooperating stationary brush stops at different heights in said seat adapted to selectively overlie said brush, a brush adapted to be reversibly positioned in said seat having portions adapted to selectively seat under and cooperate with one of said pairs of stops depending on its position in said seat.

10. In a suction cleaner agitator, a body comprising an elongated brush seat having fixed ends and brush stops at one of said ends, one of said 15 stops being higher in said seat than a second stop, a brush, fixed means on said brush adapted to underlie and contact said higher stop in one position of said brush, fixed means on said brush to underlie contact said second stop in a second 20 position, and means to hold said brush in said seat in either position against one of said stops.

25. 7. A detachable brush for a suction cleaner

agitator comprising a body, bristles in said body, and projecting ends of reduced size projecting from said body upon the same side of a vertical plane thru the longitudinal center line and separated from the main portion of the body by a shoulder.

8. In a suction cleaner agitator, a body comprising an elongated brush seat provided with a plurality of brush stops, a brush including a rigid back formed with a plurality of stops adapted to cooperate with the stops in said back, to determine the height of said brush relative to said seat and so relative to the agitator surface, certain of said stops being positioned higher on the member on which they are formed than certain of the other stops, said brush being adjustable in said seat to change the cooperating stops on said brush and on said seat for the purpose of varying the height of said brush in said seat.
